ELECTRIC CIRCUIT INTERRUPTER

Arthur Charles Ehrenberg and Gustaf Adolf Juhlin, Timperley, England, assignors to General Electric Company, a corporation of New York

Application July 15, 1932, Serial No. 632,730
In Great Britain July 29, 1931

2 Claims. (Cl. 208—150)

This invention relates to electric circuit interrupters of the type wherein the circuit interrupting contacts are immersed in insulating fluid or liquid such as oil for the purpose of extinguishing arcing, and wherein arcing between said contacts occurs within a body of liquid which is substantially segregated from the remaining liquid in an inner chamber of the interrupter hereinafter referred to as an explosion chamber.

10 A principal object of our invention is the provision of an improved electric circuit interrupter of the explosion chamber type which shall be simple and compact in construction and efficient and positive in operation.

15 In accordance with our invention the contact end of a movable member of the circuit interrupter is arranged to move in and out of the explosion chamber through an orifice in the chamber wall for the purpose of making and breaking contact with the coacting contact member. The chamber is separated by said wall from a transverse discharge passage which is traversed by the movable contact member upon leaving the explosion chamber. The arcing 20 pressure generated in the explosion chamber forces insulating liquid from the explosion chamber at the aforesaid orifice and through said discharge passage transversely of the direction of movement of said movable member. The 25 movable member then passes through another partially closed chamber in communication with said passage which is of sufficient capacity to contain an appreciable volume of insulating liquid, for example its lateral dimensions may 30 be comparable with or somewhat the same as those of the explosion chamber. The aforesaid second chamber is in communication with and followed by a second transverse passage such as that immediately preceding it. A plurality of 35 additional chambers, each with its succeeding transverse passage similar to the second chamber above described, through which the movable member of the circuit interrupter passes in succession, may be provided in certain cases. As 40 used in the present specification and claims, the term "explosion chamber" is intended to comprehend a compartment or the like adapted to contain a sufficient amount of arc-extinguishing fluid, such as oil, for a normal circuit interrupting blast as contrasted with the comparatively 45 restricted contact and exhaust passages.

Our invention will be more fully set forth in the following description referring to the accompanying drawing, and the features of novelty 50 which characterize our invention will be pointed

out with particularity in the claims annexed to and forming a part of this specification.

Referring to the drawing, Fig. 1 is a fragmentary elevational view, partly in section, of circuit interrupting apparatus embodying our invention; Fig. 2 is a plan view of the apparatus shown in Fig. 1; Fig. 3 is a view, similar to that of Fig. 1, showing a modified form of the circuit interrupting apparatus; Fig. 4 is a plan view of the apparatus shown in Fig. 3, and Fig. 5 is 5 a plan view of a detail of construction.

The circuit interrupter illustrated is of the two-pole bridge connected type, one pole only being shown in the interest of clearness, wherein the explosion chamber structure of both poles 15 and the bridging conductor are immersed in an insulating oil contained in a circuit breaker tank.

Referring to Fig. 1 of the drawing, the movable contact member 1 of the circuit interrupter which is carried at one end of the bridging conductor is arranged to move in and out of an explosion chamber 2 to make contact with the coacting fixed contact member 3 within the chamber, through insulating structure including an orifice 4 in a partition 5. This partition separates the chamber 2 from a transverse discharge passage 6 formed between the partition and a parallel insulating partition 7 spaced therefrom by a spacing washer 8 of insulating material which is shown in plan in Fig. 5. The 20 width of the passage 6 formed in the aforesaid insulating structure varies throughout its length as shown in Fig. 5, tapering towards a throat portion 9 at the part through which the movable member 1 passes, and diverging again to its 25 outlet, as shown at 10.

In the arrangement shown in Figs. 1 and 2, a small vertical wall 10 extends across the explosion chamber 2 between opposite sides of the wall 19 of the chamber and extends upwardly 40 somewhat beyond half the height of the explosion chamber. An orifice 20 is provided in the partition 5 between the side of the wall 10 remote from the fixed contact 3 and the inner side of the bounding wall 19 of the explosion 45 chamber. This orifice 20 places the walled off portion of the explosion chamber in communication with the passageway 6.

Below the partition 7 is formed a partially closed chamber 11 of substantially cylindrical 50 form, which is bounded on its underside by a horizontal partition 12. Orifices 13 and 14, in the partitions 7 and 12 respectively, allow the passage therethrough of the movable member 1. Immediately below the partition 12 is formed 55

5 a second transverse passage 15 similar in configuration to the passage 6 and bounded on its lower side by a bottom partition 16 provided with an orifice 17 through which the movable member 1 may pass, and spaced from the partition 12 by a spacing washer 8a, similar to the washer 8.

10 The diameter of the chamber 11 denoted in Figs. 2 and 4 by the dotted line 21 is substantially equal to the width of the explosion chamber 2 and its height is such that an appreciable volume of insulating liquid may be contained therein.

15 It will be observed that the movable contact member in opening the circuit passes through a series of chambers, each holding a considerable volume of the insulating liquid and communicating with each other by means of the orifices through which said movable member travels, 20 and each communicating by way of said orifice or orifices and the transverse passages with the main body of liquid outside the explosion chamber structure.

25 In operation, lowering of the movable contact 1 to open the circuit causes formation of an arc within the main explosion chamber 2 which generates and builds up high pressure within the chamber due to the decomposing action of the arc on the insulating liquid. As 30 the contact 1 continues its downward movement and passes through and clears the transverse passage 6, the arc if lengthened to this point, is subjected to a transverse blast of insulating liquid from the chamber 2 by way of 35 the communicating orifice 20. This blast is due to the fact that the chamber 2 is substantially pressure confining immediately subsequent to clearing of the restricted transverse passage 6 except by way of said passage. Further extinguishing action is had when the contact 40 passes through the second chamber 11 and the transverse passage 15. The pressure in the main chamber 2 and also that generated in the chamber 11 combine to force at high velocity 45 the insulating liquid through both the transverse passage 15 and the contact opening 17. The arc is, therefore, finally subjected to high velocity transverse and longitudinal blasts of insulating liquid, the volume of liquid in the chamber 11 insuring an adequate blast through the contact 1. 50 In case additional chambers are added to the above arrangement, the arc is subjected to successive transverse blasts from the respective chambers during the opening movement of 55 contact 1.

55 In the arrangement shown in Figs. 3 and 4 the wall 18 within the explosion chamber 2 and the passageway 20 in the partition 5, whereby the walled off portion of the explosion pot is put into connection with the passageway 6, are omitted; the explosion pot 9 is thus conveniently of circular formation and is directly in communication with the transverse passage 6 through the movable contact opening 4.

60 In some cases the first or some of the transverse passages which are provided between the explosion chambers may have communication with associated chambers by means of addition-

al openings other than those through which the movable contact passes.

65 It should be understood that our invention is not limited to specific details of construction and arrangement thereof herein illustrated, and that changes and modifications may occur to one skilled in the art without departing from the spirit of our invention.

70 What we claim as new and desire to secure by Letters Patent of the United States, is:

75 1. A fluid-immersed circuit interrupter of the explosion chamber type comprising relatively movable contacts, wall structure forming a main explosion chamber in which said contacts engage, a comparatively restricted exhaust passage 15 and a second explosion chamber, said main chamber having a passage communicating with said restricted passage through which one of said contacts is operable, said restricted passage extending transversely of and through the path 20 of said operable contact, said main chamber being substantially pressure confining immediately subsequent to clearing of said restricted passage by said operable contact except by way of said restricted passage, and said second explosion 25 chamber being substantially pressure confining except for two passages at opposite ends thereof, one of said passages communicating with said restricted passage and the other forming an exhaust passage for said second chamber, said operable contact upon opening of the circuit passing in sequence through said main explosion chamber, restricted exhaust passage and second explosion chamber respectively by way of said 30 passages.

35 2. A fluid-immersed circuit interrupter of the explosion chamber type comprising coacting fixed and movable contacts, wall structure including insulating members forming a main explosion chamber in which the fixed contact is disposed, an exhaust passage restricted in volume as compared with said main explosion chamber, a second explosion chamber and a second correspondingly restricted exhaust passage, said main chamber having a passage 40 through which the movable contact coacts with said fixed contact communicating with said first restricted passage, said first restricted passage extending transversely of and through the path of said movable contact, said main chamber being substantially pressure confining immediately 45 subsequent to clearing of said first restricted passage by said movable contact except for said first restricted exhaust passage, said second explosion chamber being substantially pressure 50 confining except for a passage at one end communicating with said first restricted passage and a passage at the opposite end communicating with said second restricted passage, said second restricted passage likewise extending transversely of and through the path of said movable contact, said movable contact upon opening of the circuit passing in sequence through said main explosion chamber, first restricted passage, second 55 explosion chamber and second restricted 60 passage respectively.
